UNITED STATES PATENT OFFICE.

BENGT SWANSON LEVEEN, OF ALBANY, NEW YORK.

COMBINED TABLE, CHAIR, AND STOOL.

SPECIFICATION forming part of Letters Patent No. 681,235, dated August 27, 1901.

Application filed June 28, 1900. Serial No. 21,336. (No model.)

To all whom it may concern:

Be it known that I, BENGT SWANSON LEVEEN, a citizen of the United States, residing at Albany, in the county of Albany and State of New York, have invented a new and useful Combined Table, Chair, and Stool, of which the following is a specification.

This invention relates to improvements in a combined chair, table, and stool; and the object thereof is to provide a simple, light, and inexpensive article of furniture which may be quickly and readily converted into either of the above articles mentioned and which is so constructed that the various parts thereof may be folded so as to be contained in a box-like body, which constitutes the top of the table or the seat of the chair, so that it may be conveniently carried from place to place.

20 The invention consists in the novel features of construction, which will be hereinafter fully described, particularly pointed out in the claims, and clearly illustrated by the accompanying drawings, in which—

25 Figure 1 is a perspective view of my invention, showing the same adapted for use as a table. Fig. 2 is a similar view showing the position of the parts when the invention is used as a chair. Fig. 3 is a sectional detail view of the collar carrying the supporting-legs, showing the locking device. Fig. 4 is a detail view of the collar carrying the supporting-arms, showing the manner of connecting the latter therewith. Fig. 5 is a sectional view through the box, showing the same closed.

Referring now more particularly to the drawings, A designates a collar having a circumferential flange B, to which the upper ends of the curved supporting-legs C are radially pivoted. A standard D is vertically movable through said collar and carries at its lower end a caster E and a circumferential flange F, to which the inner ends of the brace G are pivoted, the outer ends of such brace being pivotally connected with the legs C. The collar is provided with any preferred form of locking device for the purpose of holding the standard in the desired vertical adjustment, the locking means here illustrated consisting of a spring-held bolt H,

which has an operating-stem I projecting to the exterior of the collar, so that it may be retracted from suitable apertures J, formed in the standard in vertical alinement.

55

The upper end of the standard is threaded to receive a collar K, carrying the supporting-arms L, said supporting-arms extending radially from the collar and having their inner ends curved, which said curved ends are 60 movable in passages M, formed in the collar. By reason of this construction the arms may be folded inwardly when the invention is not in use and quickly moved to horizontal position to support the box-like body N or the 65 flexible seat portion O, said arms being formed on their inner ends with stops to prevent their entire withdrawal from the collar. The upper threaded end of the standard projects beyond the collar K when the same is in position 70 thereon and is adapted to extend through an opening formed in the bottom wall of the box N and receive a nut P, which tightly clamps said box in position, resting upon the supporting-arms L. Said box N is 75 formed with a swinging end Q, which when the invention is used as a table is held in position, closing the end of the box by a suitable catch carried by the swinging top or lid R, which is hinged at its end edges to the 80 opposite end wall of the box. Braces S are provided for holding said lid raised to constitute a back for the invention when used as a chair, each of said braces consisting of two members, respectively, hinged to the 85 inner side of the lid and the side wall of the box and pivotally connected together at their opposing ends, said brace members carrying the coacting locking members T and U, which lock the brace in its extended position, holding the lid raised. The brace members hinged to the sides of the box are formed with extensions a beyond their pivotal points, which extensions at their lower ends engage in grooves b, formed in the bottom wall of the box, so that the braces are 90 guided in their lower ends when the lid is raised.

95 To convert the table into a chair, the locking-bolt is retracted and the standard lowered until the caster carried thereby rests upon the floor. The swinging end of the box 100

is then dropped and the lid raised. Thus a comfortable chair is provided having a back and arm rests.

When the invention is not in use, the box 5 is removed from the standard, as is also the collar and supporting-arms, and the supporting-legs folded by moving the collar upon the standard. The standard and folded legs and collar and the folded supporting-arms are 10 placed in the box, which latter may be conveniently carried from place to place.

From the above description it will be seen that I have produced a very simple construction of combined table, chair, and stool which 15 is especially convenient and useful when camping and which also forms a neat article of furniture for the household.

Having thus fully described my invention, what I claim as new, and desire to secure by 20 Letters Patent of the United States, is—

1. In an article of the character described, the combination with a suitable support, of a box-like body carried by said support, having

a hinged end and top, braces for holding said top raised, each of said braces comprising 25 two members pivoted at their respective ends to said swinging top and the body and pivoted together at their opposing ends, and locking devices carried by the opposing ends of said brace members and coacting with each 30 other and holding the brace members in alignment, substantially as described.

2. In an article of the character described, the combination of a standard threaded at its upper end, a removable collar positioned 35 upon said threaded end, folding arms carried by said collar, a seat portion resting upon said arms and perforated to receive the threaded end of the standard which projects therethrough, and a clamping-nut upon said projecting end of the standard, substantially as described.

BENGT SWANSON LEVEEN.
